(57) **CLAIM**

I claim the ornamental design for a frozen beverage production machine, as shown and described.

DESCRIPTION

FIG. 1.1 is a rear view of my new design for a frozen beverage production machine;

FIG. 1.2 is a bottom view thereof;

FIG. 1.3 is a top view thereof;

FIG. 1.4 is a right side view thereof;

FIG. 1.5 is a front view thereof;

FIG. 1.6 is a left side view thereof; and

FIG. 1.7 is a perspective view thereof.

The broken lines form no part of the claimed design.
